J. C. HOWARD

WATCHCASE

Filed Jan. 29, 1923

FIG. 1

FIG. 2

FIG. 3

Inventor:

Joseph C. Howard

by Sheridan James of Glendale
Calif.

UNITED STATES PATENT OFFICE.

JOSEPH C. HOWARD, OF CHICAGO, ILLINOIS.

WATCHCASE.

Application filed January 29, 1923. Serial No. 615,473.

To all whom it may concern:

Be it known that I, JOSEPH C. HOWARD, a citizen of the United States, residing at Chicago, in the county of Cook and State of Illinois, have invented certain new and useful Improvements in Watchcases, of which the following is a specification.

This invention relates to improvements in watch cases, and more particularly to cases 10 of the two-piece type wherein provision is made for the mounting of the winding and setting stem through the joint at which the two pieces of the case come together when closed.

15 One object of the invention is to provide in a case of this character, means for rendering the same dust proof at the point of entrance of the stem. Other objects will also appear from the following specification taken in connection with the accompanying drawings 20 wherein one form of the invention is illustrated.

In the drawings—

Figure 1 is a top plan view of a watch case, 25 showing the present improvements embodied therein;

Fig. 2 is a top plan view of the case showing the same open; and

Fig. 3 is a sectional view taken on the line 30 3, 3 of Fig. 2.

Referring more in detail to the drawings, the watch case in its entirety is designated by reference character 10, said case being shown as of the elongated rectangular type, 35 such as now commonly used for the so-called wrist watches. The body portion of the case bears reference character 11 and the cap or cover portion thereof is shown at 12, the latter being hinged as at 13 to the body portion so that the same may be readily removed 40 or swung back, as shown in Fig. 2, to permit of access to the watch movement, designated generally by reference character 14. The winding and setting stem of the movement 45 is shown at 15 and extends through an opening 16 in the case formed by the complementary grooves 16^a and 16^b formed in the body portion and the cap thereof respectively.

50 Mounted on the edge of the case and surrounding the opening 16 is a housing 17, said housing being of two-part construction, one part being carried by the body portion of the case and the other part by the cap or cover thereof. These housing parts may be formed integrally with the parts of the

case carrying the same, or, if desired, may be formed separately and suitably attached thereto. Mounted within housing 17 is a collar 18 of packing material, the stem 15 60 slidably engaging through said collar as shown more clearly in Figs. 2 and 3. The head 19 of the stem is slightly greater in diameter than the diameter of the housing or packing box 17 and is provided with an annular depression 20 in its under face, said depression being of a size to receive the outer end of the packing box 17 when the stem is in its normal position, as shown in Figs. 1 and 3. The stem illustrated is of the type 70 which is employed both for winding and setting, the stem being pulled out, as shown in Fig. 2 for setting. After a setting operation, the stem is pushed inwardly to its normal position in which position it may be used for winding. The packing collar 18 very snugly fits the stem 15 but at the same time permits of the sliding in and out of the same. As will be observed, the construction of the housing 17 80 in two parts which come together when the case is closed enables the packing ring or collar 18 being very easily positioned or replaced should occasion require. The packing ring may be made of any one of a number 85 of different materials, such as hard rubber, gutta-percha, fiber, lead, etc., and in practice has been found to very effectively prevent the entrance of dust, grit and the like into the case.

90 A suitable catch (not shown) is provided for removably securing or holding the two parts of the case together when in closed relation, as will be readily appreciated.

95 It will be apparent to those skilled in the art that the present improvements are susceptible to change and modification without departing from the spirit of the invention, and accordingly it is not desired to limit or restrict the same to the particular form herein illustrated and described, except where limitations appear in the appended claims.

What I claim is—

1. The combination with a two-piece watch case provided with a stem opening at 105 the joint between the cap and body thereof, of a packing box surrounding said opening.

2. The combination with a two-piece watch case provided with a stem opening at the joint between the cap and body thereof, of a 110 packing box surrounding said opening, said box comprising complementary sections, one

carried by the body portion of the case and the other by the cap thereof.

3. The combination with a two-piece watch case provided with a stem opening at the joint between the cap and body thereof, of a packing box surrounding said opening, said box comprising complementary sections, one carried by the body portion of the case and the other by the cap thereof, and packing

10 material housed within said box.

4. The combination with a two-piece watch case provided with a stem opening at the joint between the cap and body thereof, of a packing box surrounding said opening, and a 15 collar of packing material housed within said box and adapted to slidably receive the watch stem.

5. In combination, a watch movement, a two-piece case therefor, a winding and setting stem extending through said case, a 20 head for said stem having an annular depression therein, packing material surrounding said stem, and a box for housing said material, said box being received within the depression in said head when said stem is in 25 its normal position.

6. In a two-piece watch case, a packing box surrounding the stem opening therein, the body and cap of said case each carrying a part of said box.

In testimony whereof, I have subscribed my name,

JOSEPH C. HOWARD.
